UNITED STATES PATENT OFFICE.

CHARLES VINCENT WERTZ, OF PORTSMOUTH, OHIO, ASSIGNOR TO NATIONAL FIRE WORKS DISTRIBUTING COMPANY, OF BOSTON, MASSACHUSETTS.

TOY PISTOL.

No. 926,308.

Specification of Letters Patent. Patented June 29, 1909.

Application filed September 12, 1908. Serial No. 452,696.

To all whom it may concern:

Be it known that I, CHARLES V. WERTZ, a citizen of the United States, residing at Portsmouth, in the county of Scioto and State of Ohio, have invented certain new and useful Improvements in Toy Pistols, of which the following is a specification.

My invention relates to an improvement in toy pistols, and the object is to provide 10 means whereby an explosive tape can be fed in the path of the hammer so that it will be exploded upon the operation of the trigger.

The invention consists in many other 15 novel features of construction and combinations of parts which will be hereinafter described and pointed out in the claims.

In the accompanying drawings:—Figure 1 is a view in side elevation with a part of the handle and barrel of the gun broken away; 20 Fig. 2 is a view of the combined hammer and trigger; Fig. 3 is a view of the back; and Fig. 4. is a detail.

A represents the barrel and B the handle. The trigger 1 is pivotally mounted on a pin 2 in the rear of the barrel, and formed at the upper end is a hammer 3. The hammer is formed on the rear side so that it strikes against the back 4 of the handle. The main spring 5 is mounted on the trigger and one 30 end bears against the barrel and the other end bears against the hammer 3, causing it to return to its normal position or causing the hammer to lie against the anvil 6 formed on the back 4. The back 4 is removably 35 held between the sides 7, 7 of the handle B, and is provided at its upper end with grooves 8, in which are received pins or lugs 9 formed on the sides of the handle at the upper end thereof. A slot 10 is formed in one of the 40 sides 7 of the handle, in which an arm 11 is received, which is formed on the back 4. A pin 12 is formed on the arm at its lower end on which is mounted the explosive tape 13. A spring 14 is held between the sides by pins 45 15, 15, which pass through the sides 7, 7. This spring extends upwardly and causes the tape to be held against the back 4, whereby it can be fed along to the anvil 6 and hammer 3. On the rear side of the hammer a recess 50 16 is formed in which is received one end of a spring 17. The spring passes around the wall of the recess and is secured at one end in a slot 18 formed in the hammer. The spring passes downwardly from the hammer and

curves upwardly beneath a pin 19, which is 55 secured to the sides 7, 7, to the tape 13. This spring engages the tape and causes it to be fed up to the anvil 6 when the hammer is forced forward as the trigger is drawn rearwardly, and upon releasing the trigger the hammer will be forced rearwardly by the spring 5, causing it to come in contact with the explosive tape on the anvil 6, thereby 60 causing an explosion. 65

From the foregoing it will be seen that I have provided a very simple means for feeding the tape to be exploded and the manner of operating the hammer for causing the explosion. Again the removable back can be 70 removed by simply forcing up the lower end thereof and sliding it forward until it is released from the pins 9. When it is desired to place a new tape on the pin 12 of the arm 11, the back can be swung upwardly upon 75 the pins 9 and the new tape placed on the pin. The tape will be drawn along until it reaches approximately the upper end of the back where it will be engaged by the springs 17 and 14, when the back can be forced back 80 into position and the pistol is then ready for use. The spring 14 performs a very important function as it retains the tape in its proper position along the back 4 and prevents the tape from slipping rearwardly 85 down into the magazine or handle of the pistol when the feed spring 17 works down for feeding the tape in the path of the hammer. It also prevents the back fire from the exploding cap from flashing back and exploding 90 the rest of the ammunition or tape.

It is evident that more or less slight changes might be resorted to in the form and arrangement of the several parts described without departing from the spirit and scope 95 of my invention, and hence I do not wish to be limited to the exact construction herein set forth, but:—

Having fully described my invention, what I claim as new and desire to secure by Letters Patent, is:—

1. A pistol comprising a barrel and handle, a back pivotally mounted on the handle, and means on the back for carrying an explosive tape. 100

2. A pistol comprising a barrel and handle, a removable back on the handle, and means on the back for carrying an explosive tape. 105

3. A pistol comprising a barrel and handle,

a back pivotally mounted on the handle, means on the back for carrying an explosive tape, a hammer and means for guiding the tape into the path of the hammer.

5 4. A pistol comprising a barrel and handle, a removable back on the handle, means on the back adapted to receive an explosive tape, a hammer, a trigger on the hammer, and means on the hammer for feeding the 10 tape into the path of the hammer.

5. A pistol comprising a barrel and handle, a removable back on the handle adapted to receive an explosive tape, a trigger, a hammer on the trigger for exploding the tape, 15 and means for guiding the tape into the path of the hammer.

6. A toy pistol comprising a magazine adapted to receive an explosive tape therein, a spring for guiding the tape, a trigger, a hammer on the trigger and a spring on the hammer adapted to engage the tape for feeding it in the path of the hammer as the hammer is actuated preparatory to striking the tape.

7. A toy pistol comprising a barrel and handle, said handle adapted to receive an explosive tape therein, a removable handle back, an anvil formed on the back, a trigger, a hammer on the trigger, and means for feeding the tape on to the anvil whereby it is exploded upon the operation of the hammer.

8. A toy pistol comprising a handle, a removable back, means on the back for receiving an explosive tape, a spring supported in the handle for guiding the tape, a trigger, a hammer on the trigger, and a spring connected to the trigger for feeding the tape in

the path of the hammer whereby it is exploded upon the operation of the hammer.

9. A toy pistol comprising a barrel and handle, a removable back, an anvil formed on the back, means for supporting an explosive tape on the back, a spring for guiding the tape, a trigger, a hammer on the trigger, and means on the hammer for feeding the tape to the anvil where it is exploded upon the 45 operation of the hammer.

10. A toy pistol comprising a barrel and handle, a back, means for pivotally supporting the back on the handle, said back capable of being removed from the handle without interfering with the pivotally supporting means.

11. A toy pistol comprising a barrel and handle, pins formed on the handle, and a back pivotally and removably mounted on the pins.

12. A pistol comprising a handle having a slot formed in one side thereof, a removable back pivotally mounted on the handle, an arm on the back received in the slot in the handle, said arm adapted to receive the explosive tape thereon, a trigger, a hammer on the trigger and means on the hammer for feeding the tape into the path of the hammer as the hammer is actuated preparatory to 65 exploding the tape.

In testimony whereof I affix my signature, in the presence of two witnesses.

CHARLES VINCENT WERTZ.
